Fig. 1.

Fig. 1. is a detailed electrical circuit diagram for a device labeled 'A'. The circuit includes various components such as resistors, capacitors, and switches, connected through a complex network of lines. Key components labeled include 100, 101, 102, 103, 104, 105, 106, 107, 108, 109, 110, 111, 112, 113, 114, 115, 116, 117, 118, 119, 120, 121, 122, 123, and 125. A small inset diagram at the bottom left shows a component labeled 'A' with a switch and a dial.

UNITED STATES PATENT OFFICE.

WINFRED T. POWELL, OF ROCHESTER, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed January 4, 1921. Serial No. 434,991.

To all whom it may concern:

Be it known that I, WINFRED T. POWELL, a citizen of the United States of America, residing at Rochester, in the county of Monroe, State of New York, have invented certain new and useful Improvements in Telephone-Exchange Systems, of which the following is a full, clear, concise, and exact description.

10 This invention relates to telephone exchange systems, and more particularly, to telephone systems in which connections are established by means of automatic switches under the control of calling subscribers and 15 in which telephone service is charged by means of a coin device at the subscriber's substation.

In systems of this general character, it is the usual practice to control the calling subscriber's coin device to charge for the service by means of controlling mechanism at the central office which causes the deposited coin to be collected if the established connection is successful, that is, if the called 25 subscriber responds, and to refund the coin if the connection is unsuccessful. In order to effect a saving in apparatus it has been proposed to provide controlling mechanism for controlling subscriber's 30 service charging devices which is common to a plurality of groups of automatic switches and which, therefore, may be associated with any one of a plurality of established connections.

35 In systems in which the automatic switches are power-driven under the control of a register sender at the central office, the sender is associated with the automatic switches employed to establish a connection, through 40 the medium of a sender switch which functions immediately following the initiation of a call. As soon as a connection has been established through the functioning of the sender, the sender is automatically disassociated from the established connection and is then free to be employed in the establishment of other connections. Inasmuch as it is necessary to provide means associated with the sender for causing a deposited coin to be refunded, in the event that the calling subscriber abandons a call prior to its completion and thus prior to the disconnection of the sender, it is proposed to provide the sender with mechanism for completely controlling the operation of sub-

scriber's service charging devices at all stages of initiated connections and to thus avoid the necessity of employing auxiliary controlling mechanism.

To accomplish this result since at the time 60 it is desirable to charge for the service following the completion of a connection, the sender has been disassociated from the connection, it is necessary to temporarily reassociate an office sender with the established 65 connection. In the system herein disclosed the sender is reassociated with the connection immediately following the restoration of the calling subscriber's receiver to its switchhook when the calling subscriber initiates the release of the connection.

It is, therefore, an object of this invention to provide in an exchange system of large capacity an improved controlling mechanism and method for controlling subscriber's 75 service charging devices.

It is more specifically an object of this invention to provide controlling mechanism for controlling service charging devices associated with an office sender and to provide a single means for associating the office sender and associated controlling mechanism with an established connection to control the charging device.

A feature of the invention resides in the 85 provision of an office sender common to a plurality of groups of automatic switches for controlling the switches to establish connections between subscribers' lines and provided with mechanism for controlling service charging devices on calling subscribers' 90 lines at all stages in the establishment of connections.

A further feature resides in the provision of means for associating a common office 95 sender with a subscriber's district selector switch for controlling the establishment of a desired connection, for disconnecting the sender upon the completion of the establishment of the connection and for reassociating 100 a sender and associated controlling mechanism with an established connection upon the initiation of the release of the connection for collecting a coin deposited in the subscriber's service charging device, or for refunding the coin dependent upon the success 105 of the established connection.

Such other features as are contemplated by the present invention will become more apparent from the following description 110

and the appended claims. The invention will now be described in connection with one specific embodiment of the genus of the invention. In the drawings Figs. 1 to 5 inclusive illustrate diagrammatically so much of the circuits and apparatus of a telephone exchange system as are necessary to embody the features of the present invention.

Fig. 1 shows a calling subscriber's line together with a distributing switch individual to such line; Fig. 2 shows a district selector switch and a sender finder switch together with the circuits and controlling mechanism associated therewith; Fig. 3 shows a portion of the circuits of an incoming selector switch, final selector switch and a called subscriber's line; Fig. 4 shows the circuits and apparatus of the service charging controlling mechanism; Fig. 5 shows a portion of the circuits of an office sender with which the controlling mechanism of Fig. 4 is permanently associated; and Fig. 6 is a diagram illustrating the manner in which the several figures of the drawing should be arranged to disclose a complete organization of the circuits involved in the invention.

The selector switches disclosed in Figs. 2 and 3 may be of the type disclosed in the patent to E. B. Craft and J. N. Reynolds 30 1,123,696 issued January 5, 1915. In Fig. 3 only the brushes of the incoming and final selector switches and certain of the controlling circuits have been disclosed. For a full disclosure of these switches and associated circuits, reference may be had to the patent to E. H. Mills, No. 1,504,261, issued August 12, 1924.

The sender diagrammatically disclosed in Fig. 5 may be of the type disclosed in the patent issued to E. H. Mills hereinbefore referred to, only such portions of the sender being disclosed herein as are necessary to an understanding of the invention. The sequence switch cams disclosed within the dotted rectangle are associated in the well-known manner with a sequence switch power magnet (not shown), and are employed to control certain circuits of the sender. In the lower right-hand corner of Fig. 5, a register steering switch is disclosed which is instrumental in associating the impulsing circuit extending to the subscriber's line successively with a plurality of step-by-step registers (not shown) for registering the several digits of the designation of a desired line. For a full disclosure of the circuits of the sender and the manner in which they function, reference may be had to the aforementioned patent issued to E. H. Mills.

Detailed description of operation.

The manner in which the system is organized will best be presented in connection with a description of its mode of operation. It will be assumed that the subscriber at

substation A desires to establish a connection with the substation B whose directory number is L I S penard 9532. The calling subscriber upon initiating the call removes his receiver from the switchhook and closes a circuit for the line relay 101 of the trunk hunting switch 100, which circuit may be traced from battery through the right-hand winding of relay 101, innermost lower armature and back contact of cut-off relay 102, over line conductor 103, through the substation of the subscriber's line and thence back over line conductor 104 to ground at the upper armature and back contact of cut-off relay 102. Relay 101 energizes in this circuit and closes a circuit for the stepping magnet 105, which circuit may be traced from battery, through the winding and armature contacts of magnet 105, conductor 106, the lowermost armature and back contact of relay 102, the right-hand armature and front contact of relay 101, conductor 107 and thence to ground through the wiper 108 and the normal terminal of the bank to which this wiper has access. The magnet 105 upon energizing in this circuit advances the wipers 108, 109, 110, 111, 112 and 113 to the second terminals of the respective banks to which they have access. As the second terminal which wiper 108 now engages is permanently connected to ground, magnet 105 continues to step the wipers to the third set of terminals leading to the first of the group of trunks to which the switch 100 has access.

If the first trunk of the group is busy there will be a ground potential on the test terminal thereof appearing in the lowermost bank of the switch, and the switch will therefore continue stepping until an idle trunk is found upon the test terminal of which battery potential appears. When this battery potential is encountered, a circuit is closed from battery, through the right-hand contacts of cam 202 at the district selector switch to which the first idle trunk extends, through the inner left-hand armature and back contact of sleeve relay 226, test conductor 114, wiper 108, conductor 107, the left-hand armature and front contact and left-hand winding of relay 101, conductor 115 and thence to ground through both windings of relay 102. Relay 101 is maintained energized and relay 102 energizes in this circuit. The energization of relay 102 opens the circuit of the stepping magnet 105 at its lowermost armature and back contact and at its upper armature and front contact and intermediate armature and front contact this relay extends the conductors 103 and 104 of the subscriber's line to the wipers 111 and 113 of the switch 100 and thence to the trunk conductors 116 and 117 leading to the selected district selector. Relay 102 at its lower intermediate armature and front contact

- closes a circuit extending through the left-hand winding of sleeve relay 226, through the normal contacts of the left-hand armature of slow releasing relay 227, the lower 5 right-hand contact of cam 203 (1 to 2½), sleeve conductor 118, wiper 109, conductor 120, the lower intermediate armature and front contact of relay 102 and thence to ground through the upper winding of relay 102. The sleeve relay 226 of the district selector switch energizes in this circuit. 10
- For making the calling subscriber's line busy to all calls incoming thereto, battery potential is connected to the multiples of test 15 terminal 121 appearing in the banks of all final selector switches having access to this line, over conductor 122, wiper 110 and the off-normal segment 123 to battery. Wiper 112 through the grounded off-normal segment 124 prepares a circuit extending over conductor 125 preparatory to restoring the finder switch 100 to normal when relay 102 becomes deenergized upon the termination of the connection. 20
- Upon the energization of relay 226, a circuit is established for control relay 228 of the district selector switch 250, which circuit extends from battery through the right-hand winding of this relay, the upper contacts of cam 204, the right-hand armature and front contact of relay 226 and thence to ground through the upper right-hand contact of cam 205 (17 to 15). At its inner left-hand armature and front contact, relay 226 connects ground potential to the test conductor 114 of the selected trunk to mark the trunk busy to other line switches and at the back contact of this armature disconnects the source of battery potential which up to 30 the time the selector switch was seized marked the selector switch as idle. The locking circuit of relay 101 is now opened and the relay deenergizes. 35
- Relay 228 upon energizing closes a circuit for driving the sequence switch of the district selector out of normal position 1 into position 2, this circuit extending from battery through the magnet winding of sequence switch 200, the lower right-hand contact of cam 206 (1), the inner right-hand armature and front contact of relay 228 and thence to ground at the upper right-hand contact of cam 207 (7½ to 6). The sequence switch magnet energizes in this circuit and 45 under the control of master cam 201 drives the sequence switch into position 2, in which position a circuit is closed from battery through the left-hand winding of relay 227 and thence to ground through the upper left-hand contact of cam 205 (2 to 11). Relay 227 upon energizing closes a holding circuit for relay 226 extending through the left-hand winding of relay 226, the alternate contacts of the left-hand armature of relay 227 50 and thence to the sleeve conductor 118, over the upper right-hand contact of cam 203 (1¾ to 16), this circuit being maintained through position 16 of the sequence switch, or until relay 227 becomes deenergized. Upon reaching position 2, the sequence 55 switch connects a new busy ground to the test conductor 114 at the lower left-hand contact of cam 205, which busy ground is maintained through position 18½ of the sequence switch. 75
- Selection of an idle sender.*
- As soon as the sequence switch reaches position 1¾, a circuit is closed for the stepping magnet 229 of the sender finder SF extending from battery through the interrupter contacts and winding of magnet 229, the lower left-hand contact of cam 208, the inner right-hand armature and front contact of relay 228 and to ground at the right-hand contact of cam 207. A circuit is also closed at this time through the winding of stepping magnet 229, the winding of relays 230 and 244 in parallel and thence to ground at the upper left-hand contact of cam 209 (2 to 11). 80 Relays 230 and 244 do not energize at this time, however, since their windings are shunted by ground connected through the armature of relay 228. 85
- As soon as sequence switch 200 leaves position 1, the initial energizing circuit of relay 228 is opened at the upper contacts of cam 204, but this relay remains locked over a circuit extending from battery through its left-hand winding, its left-hand armature and front contact, the lower right-hand contact of cam 210 (1 to 6), the lower left-hand contact of cam 211 (1 to 2¼), the outer left-hand armature and front contact of relay 226, test wiper 231 of the sender finder 90 switch and to ground on busy terminals of the bank over which this wiper moves. As soon, however, as an idle sender mechanism is found, the wiper 231 will find no ground potential on the terminal corresponding to such idle sender mechanism and the control relay 228 will thereupon deenergize, opening at its inner right-hand armature and front contact the circuit extending through the stepping magnet 229 and closing at its inner right-hand armature and back contact a circuit for driving sequence switch 200 out of position 2 and into position 3. This circuit may be traced from battery through the magnet winding of sequence switch 200, the upper left-hand contact of cam 206 (2), the inner right-hand armature and back contact of relay 228 and thence to ground at the right-hand contact 100 of cam 207. 105
- As soon as relay 228 deenergizes, the shunt around the windings of relays 230 and 244 is removed at the inner right-hand armature and front contact of relay 228, and relays 230 and 244 thereupon energize in series 110 115
- 120
- 125
- 130

with magnet 229, the current flowing through this circuit, however, not being sufficient to cause the energization of the magnet. Relay 230 upon energizing closes a circuit extending from ground through the inner right-hand armature and front contact of this relay, over wiper 231 and the terminal upon which it is resting, conductor 500 and thence to battery through the left-hand winding of differential relay 501. Relay 501 energizes in this circuit and closes a circuit for advancing the time measure switch TM out of its normal position. This circuit may be traced from battery through the winding of stepping magnet 502, wiper 503 and the normal terminal of the bank with which it is associated, interrupter 504, outer left-hand armature and back contact of relay 505 and thence to ground at the armature and front contact of relay 501. Stepping magnet 502 advances the wipers of the time measure switch into position 2 under the control of interrupter 504 for measuring off a suitable time interval before relay 505 becomes energized to connect the calling subscriber's line with the registers of the sender.

As soon as the time measure switch TM reaches position 2 a circuit is established for relay 505 which may be traced from battery through the winding of this relay, bank terminal 506, wiper 507 and thence to ground. Relay 505 energizing in this circuit closes a locking circuit for itself extending through its winding, its intermediate left-hand armature and front contact and thence to ground at the armature and front contact of relay 501. At the back contact of its outer left-hand armature, relay 505 opens the circuit previously traced through the stepping magnet 502 and closes a new stepping circuit which may be traced from battery through the winding of magnet 502, the armature and back contact of this magnet, wiper 508, the second position terminal 509 with which the wiper 508 is now in engagement, the outer left-hand armature and front contact of relay 505 and thence to ground at the armature and front contact of relay 501. Stepping magnet 502 is now energized in this circuit and by means of its own self-interrupting armature contact advances the wipers of time measure switch TM to position 6, in which position the circuit of magnet 502 is opened at wiper 508. As soon as the time measure switch leaves its normal position, busy ground potential is applied to the test conductor 500 multiplied into the bank terminals of all sender finder switches having access to the seized sender. This busy potential is applied to conductor 500 over a circuit which may be traced from ground through wiper 510, the off-normal terminals of bank 511, the right-hand winding of relay 501 and thence to test conductor

500. The right-hand winding of relay 501 being shunted at this time is without effect.

Relay 505 upon energizing also closes an impulsive circuit for associating the registers of the sender with the calling subscriber's line, which may be traced from battery through the winding of stepping relay 512, conductor 513, the outer left-hand armature and back contact of relay 400, the outer left-hand armature and back contact of relay 401, conductor 403, the right-hand armature and front contact of relay 505, conductor 514, wiper 236, the inner left-hand armature and front contact of relay 230, conductor 235, the lower left-hand contact of cam 213, the winding of relay 234, trunk conductor 116, wiper 111 of switch 100, the innermost lower armature and front contact of relay 102, conductor 103 through the calling subscriber's sending dial S, conductor 104, the upper armature and front contact of relay 102, wiper 113, trunk conductor 117, the lower left-hand contact of cam 212, conductor 233, the outer left-hand armature and front contact of relay 230, wiper 232, conductor 515, the inner left-hand armature and front contact of relay 505, conductor 402, the outer right-hand armature and back contact of relay 401, the outer right-hand armature and back contact of relay 400, conductor 404 and thence to ground through the winding of retardation coil 516. The stepping relay 512 energizes in this circuit and at its right-hand armature and front contact closes a circuit for the slow releasing relay 517. This circuit extending from battery through the winding of relay 517 and thence to ground through the right-hand armature and front contact of relay 512.

Upon the initial energization of relay 501, a circuit was also established for initiating the operation of the monitoring time measure switch M. The starting circuit for this switch may be traced from battery through the winding of starting relay 405, the normally closed contacts associated with its inner left-hand armature, wiper 406 of the switch M and the normal bank terminal 110 upon which it is resting, conductor 407, thence to ground at the armature and front contact of relay 501. Relay 405 energizing in this circuit establishes a locking circuit for itself independent of the wiper 406 which may be traced through its winding, the make contact of its inner left-hand armature, conductor 408 and thence to ground on conductor 407. At its intermediate right-hand armature, relay 405 establishes a circuit for slow-to-release relay 409 which may be traced from ground through the intermediate right-hand armature and front contact of relay 405, the inner left-hand armature and back contact of relay 410, wiper 477, the normal bank terminal 115 upon

which it is resting, the winding of relay 409, conductor 411 and to battery through the right-hand armature and back contact of the coin translator register relay 518. Relay 409 upon energizing closes a locking circuit for itself extending from conductor 411, through its winding, its left-hand armature and front contact, the outer right-hand armature and back contact of coin collection relay 412, conductor 413, the armature and back contact of coin test relay 414, the inner left-hand armature and back contact of relay 415 and thence to ground at the outer right-hand armature and front contact of relay 405. At its right-hand armature and front contact relay 409 establishes a circuit for relay 416 which may be traced from battery on conductor 411, through the winding of relay 416 and thence to ground at the right-hand armature and front contact of relay 409 and a circuit for relay 410 which may be traced from battery through the right-hand winding of relay 410, wiper 417 and the normal bank terminal upon which the wiper is resting and thence to ground at the right-hand armature and front contact of relay 409. The energization of relay 416 is without effect at this time. Relay 410 upon energizing establishes a stepping circuit for the stepping magnet 418 of the switch M which may be traced from battery through the winding and armature contact of magnet 418, the right-hand armature and front contact of relay 410, wiper 417 and the normal bank terminal upon which it is resting and thence to ground at the right-hand armature and front contact of relay 409. Stepping magnet 418 advances the wipers of switch M one step when the energizing circuit of relay 410 is opened at switch wiper 417 and the previously traced circuit through the winding of stepping magnet 418 is opened at the armature contact of relay 410. With relay 410 deenergized and switch M in position 1, a new driving circuit is closed for the switch M through the winding of stepping magnet 418 and the slow interrupter 419 which may be traced from battery, through the winding of magnet 418, right-hand armature and back contact of relay 410, interrupter 419, the inner left-hand armature and back contact of relay 420, the No. 1 terminal in the bank with which wiper 477 is associated, wiper 477, the inner left-hand armature and back contact of relay 410 and thence to ground at the intermediate right-hand armature and front contact of relay 405.

Under the influence of the slow interrupter 419, switch M is advanced into position 3 measuring off time sufficient to enable the calling subscriber to dial the first digit. If the calling subscriber fails to dial the first digit within the time measured by the ad-

vance of switch M to position 3, a circuit is established for displaying a signal on the sender monitoring lamp 421, which circuit may be traced from grounded battery through the lamp 421, the outer left-hand armature and back contact of relay 415, bank terminal 422, wiper 423, the outer left-hand armature and back contact of relay 410 and thence to ground at the intermediate right-hand armature and front contact 75 of relay 405. At the same time a signal is displayed by the auxiliary pilot lamp 424, the lamp 424 being illuminated in the circuit which may be traced through the right-hand armature and back contact of relay 420, contact terminal 425, wiper 477, the inner left-hand armature and back contact of relay 410 and thence to ground at the intermediate right-hand armature and front contact of relay 405. The monitoring operator noting the illumination of lamps 421 and 424 takes the necessary steps to ascertain the trouble on the calling line, or the reason why the calling subscriber has failed to commence dialing. 80

Assuming that the calling subscriber does proceed to dial the first digit of the number of the desired connection within the specified time interval, and further, assuming that the subscriber desires a connection with a subscriber's line B which is listed in the directory as L I S penard 9532 and that the calling line is to be reached through a district selector switch 250, an incoming selector switch 300 and a final selector switch 350, the subscriber proceeds to dial three letters corresponding to the office designation of the desired line and then dials four digits representing the number of the line in such office. In the case assumed the calling subscriber will dial the three letters L I S and will then dial the numerals 9532. The three letters which represent the office code will in the manner fully set forth in the patent issued to E. H. Mills hereinbefore referred to, cause the setting of the code registers of the sender for controlling the setting of the district selector switch 250 for determining the adjustment of the circuit of the sender and for determining the positioning of the sequence switch of the district selector switch for talking selection. 105

In response to the first impulse dialed by the calling subscriber in accordance with the first letter of the office designation, the stepping relay 512 deenergizes and closes a circuit for the stepping magnet (not shown) of the first code register, which stepping circuit may be traced in part from ground through the right-hand armature and back contact of relay 512, the right-hand armature and front contact of relay 517, the winding of slow-to-release relay 519, wiper 520 and the normal position contact upon 120

125

130

which it is resting, thence over conductor 521 through the winding of the stepping magnet of the first code register. During the sending of the series of impulses, slow-to-release relay 519 remains energized and closes a circuit for the stepping magnet 522 of the register steering switch RS which may be traced from battery, through the winding of magnet 522, the armature contact of relay 519 and thence to ground at the left-hand armature and contact of relay 517. Upon the completion of the series of impulses, relay 519 deenergizes opening the previously traced circuit through the stepping magnet 522 and the magnet 522 upon deenergizing advances the wipers 520, 523 and 524 of the register steering switch from normal position to position 1. In a similar manner, impulses are transmitted through the winding of stepping relay 512 to adjust the other registers of the sender, the register steering switch RS advancing step by step to associate successive registers with the armature contact of the stepping relay 512.

As soon as the steering switch advances its wipers to the No. 1 terminals of its banks, a circuit is established for continuing the advance of the monitoring time measure switch M out of position 3. This circuit may be traced from battery through the right-hand winding of relay 410, wiper 417, the No. 3 terminal of the bank with which it is associated, conductor 426, the No. 1 terminal with which the wiper 523 of the switch RS is in engagement, wiper 523 and thence to ground at the left-hand armature and front contact of relay 517. Relay 410 energizes in this circuit and closes a circuit for the stepping magnet 418 of the switch M which may be traced from battery through the winding, armature and back contact of stepping magnet 418, the right-hand armature and front contact of relay 410, wiper 417 and thence to ground over the circuit previously traced at the right-hand armature and front contact of relay 517. Stepping magnet 418 now advances the wipers of switch M from position 3 to position 5, when the stepping circuit is interrupted at wiper 417. As soon as wiper 417 leaves position 4, the circuit of relay 410 is opened and relay 410 deenergizes, establishing a new driving circuit for switch M for advancing the wipers of the switch under the control of the slow interrupter 419. This driving circuit may be traced from battery through the winding of magnet 418, the right-hand armature and back contact of relay 410, interrupter 419, the inner left-hand armature and back contact of relay 420, Nos. 4, 5 and 6 terminals of the bank associated with wiper 477, wiper 477, the inner left-hand armature and back contact of relay 410, and thence to ground

at the intermediate right-hand armature and front contact of relay 405.

During the advancement of the wipers of switch M from position 4 into position 7, an interval of time is measured sufficient to enable the calling subscriber to completely dial the number of the desired connection. If the subscriber has not completed dialing at the time the switch M reaches position 7, the switch stops in position 7 and a circuit is established through resistance 427 for the sender monitor lamp 421 for lighting the lamp dimly for indicating unfinished dialing. The circuit of lamp 421 may be traced from battery through the lamp, the outer left-hand armature and back contact of relay 415, resistance element 427, the Nos. 7 terminal of the bank with which wiper 423 is associated, wiper 423, the outer left-hand armature and back contact of relay 410 and thence to ground at the intermediate right-hand armature and front contact of relay 405. At the same time the pilot lamp 424 is illuminated over the previously traced circuit. The operator noting the dim illumination of lamp 421, then proceeds to take the necessary steps to ascertain the trouble.

As soon as the subscriber has dialed the second code digit, the register steering switch advances to position 2 and a circuit is established for relay 525, which circuit may be traced from battery through the left-hand winding of relay 525, bank terminal 526, wiper 523 and thence to ground at the left-hand armature and contact of relay 517. Relay 525 upon energizing closes a locking circuit for itself extending through its right-hand winding, its right-hand armature and front contact and thence to ground through wiper 510 of the switch TM. In the manner fully set forth in the application hereinbefore referred to, relay 525 initiates the translation of the code set up upon the code register to the translator register relays (not shown) of the sender for controlling the operation of the district selector switch 250, and further, causes the advance of the sender sequence switch 527 out of its normal position 1 into position 2 preparatory to establishing a fundamental circuit between the office sender and the district selector switch.

The fundamental circuit may be traced from battery through the left-hand winding of control relay 228 of the district selector switch, the left-hand contacts of cam 210, conductor 262, the outer right-hand armature and front contact of relay 230, wiper 237, conductor 528, the armature and back contact of relay 529, the winding of sender stepping relay 530, the winding of polarized overflow relay 531, the armature and back contact of relay 532 and thence to ground through the lower contact of cam 533 (1 to 4) and resistance element 534. Re-

lay 228 of the district selector switch and the stepping relay 530 of the office sender are energized in this circuit.

5 *Extension of connection to called line.*

Relay 228 upon energizing closes a circuit for driving sequence switch 200 of the district selector out of position 3 and into position 4. This circuit extends from battery 10 through the magnet winding of 200, the lower right-hand contact of cam 206 (3), the inner right-hand armature and front contact of relay 228 and thence to ground at the right-hand contact of cam 207 (7½ to 6). With the district selector sequence switch 200 in position 4, a circuit is now closed for the updrive magnet 238 which extends from grounded battery through the winding of magnet 238, the right-hand contact of cam 208 (4) and thence to ground 15 through the inner right-hand armature and front contact of relay 208 and the right-hand contact of cam 207. Magnet 238 upon energizing presses the depending portion of 20 the switch shaft 239 against the constantly rotating updrive drum 240, thereby causing the upward movement of the switch shaft. Upon the movement of the sequence switch 200 out of position 4, the initial energizing 25 circuit of relay 228 which extends through its left-hand winding is opened at the lower left-hand contact of cam 210, but a locking circuit for relay 228 is closed at this time through its left-hand winding, its left-hand armature and front contact and to the fundamental circuit previously traced, through the lower right-hand contact of cam 210 (1 to 6).

relay and back contact of the No. 2 counting 10 relay 536, thence over the lead 537 and to ground through the armature and front contact of relay 530. Counting relay 535 upon energizing in this circuit closes a locking circuit for itself extending from battery 75 through the winding of relay 535, the winding of relay 536, the armature and front contact of relay 535 and thence to ground at the contact of sender sequence switch cam 538 (2). The upper counting relay 536 does not energize until stepping relay 530 deenergizes at the time the brush 241 of the district selector engages the first conducting portion of segment 242. Upon the energization of relay 536, lead 537 is extended through the armature and front contact of relay 536, the armature and back contact of the No. 1' counting relay 539 and to battery through the winding of the No. 1 counting relay 540. Upon the second energization of stepping 85 relay 530, relay 540 becomes energized and locks up through the winding of relay 539 and in response to the next energization of stepping relay 530, the No. 0 counting relay 541 becomes energized, and locks up through 90 the winding of the No. 0' counting relay 542. Upon the next deenergization of stepping relay 530, the 0' counting relay 542 energizes in parallel with relay 532. Upon the energization of counting relay 542, a circuit is established for advancing the sender sequence switch 527 out of position 2 and into position 4. This circuit extends from

As the switch shaft 239 approaches its first brush selection position, the brush 241 engages the first conducting portion of the commutator segment 242 and a shunt circuit is established around the winding of the sender stepping relay 530 which may be traced from battery through the left-hand winding, left-hand armature and front contact of relay 228, the lower right-hand contact of cam 210, the upper left-hand contact of relay 211 (3 $\frac{3}{4}$ to 4), conductor 243, segment 242, brush 241 and thence to ground at the lower contact of cam 209 (9 to 7). Relay 228 is maintained energized over the shunt circuit, but sender stepping relay 530 is caused to deenergize. As the switch shaft 239 continues in its upward movement the brush 241 engages an insulating portion of the segment 242 and the shunt circuit previously traced is opened, whereby the sender stepping relay 530 is again energized. Thus, during the upward movement of the switch shaft, the sender stepping relay 530 is intermittently energized and deenergized.

Upon the energization of relay 532 the fundamental circuit is opened at the armature and back contact of this relay and as soon thereafter as the brush 241 of the district selector engages the next insulating portion of the commutator segment 242, relay 228 of the district selector deenergizes, closing a circuit for driving the district selector sequence switch 200 out of position 4 and into position 5. This circuit extends from battery through the magnet winding of sequence switch 527, the contact of sequence switch cam 543 (2), and thence to ground at the armature and front contact of relay 542. As soon as the sequence switch leaves position 2, the locking circuits of the energized counting relays are opened at the contact of cam 538.

Under the assumption that the calling subscriber has dialed the code L I S, a circuit is established upon the first energization of contact of cam 264. As soon as relay 226 deenergizes, the circuit previously traced through the updrive magnet 238 is opened at the inner right-hand armature and back

- contract of relay 228 and the upward movement of the switch shaft is arrested. With sequence switch 200 of the district selector in position 5 and the sender sequence switch 527 in position 4, the fundamental circuit previously traced is again established and relays 228 and 530 again energize. Relay 228 upon energizing causes the movement of the district selector sequence switch 200 from position 5 into position 6, the initial energizing circuit of relay 228 being opened as previously described at the lower left-hand contact of cam 210 as soon as the sequence switch leaves position 5. Relay 228, however, remains energized over the fundamental circuit through its left-hand winding, left-hand armature and front contact and the lower right-hand contact of cam 210.
- During the brush selection movement of the district selector from the time the sequence switch reaches position 3, a circuit is established through the right-hand winding of the differential relay 227, the upper contact of cam 214, the right-hand armature and front contact of relay 244, which energized in parallel with relay 230, the lower contact of cam 215 (3 to 10), wiper 245, conductor 544, the right-hand armature and back contact of advance relay 545, resistance element 546 and thence to ground at the contact of cam 547. The resistance element 546 included in this circuit is such that the current flowing in the right-hand winding of relay 227 is not sufficient to cause the differential relay 227 to become unbalanced, and relay 227 therefore remains energized over the previously traced initial energizing circuit. The circuit just traced is maintained until the district selector sequence switch leaves position 10 following the completion of the setting of all the selector switches and is established for a purpose which will hereinafter be described. Upon reaching position 6, the circuit previously traced for the updrive magnet 238 is again established through the upper right-hand contact of cam 208 (6) and the inner right-hand armature and front contact of relay 228, and in the manner previously described, the switch shaft 239 is again driven upwardly. Since at this time the tripping spindle has been rotated by the tripping magnet 227, which was energized in position 5 of sequence switch 200 over a circuit extending from battery through the winding of magnet 247 and to ground through the lower right-hand contact of cam 205 (5 to 7), the third set of brushes is now tripped upon the initial upward movement of the switch shaft 239 and during the continued upward movement of the shaft the brushes travel over the bank with which they are associated. As the switch shaft approaches its first group selection position, the brush 248 engages the first metallic portion of the group selection segment 249 of the commutator and a circuit is closed in shunt of the winding of the sender stepping relay 530, which may be traced from battery through the left-hand winding, left-hand armature and front contact of relay 228, right-hand contacts of cam 210, segment 249, brush 248 and thence to ground at the lower contact of cam 209. Relay 228 is maintained energized over this circuit, but sender stepping relay 530 becomes deenergized. As the switch shaft continues in its upward movement and the brush 248 engages the first insulating portion of commutator segment 249, the shunt circuit is opened and sender stepping relay 530 again energizes. In this manner during the upward movement of the switch shaft in its group selection movement, the sender stepping relay 530 intermittently energizes and deenergizes.
- It will be assumed that the code which the calling subscriber has dialed has so set the registers of the sender as to prepare a circuit for the No. 0 counting relay 541 upon the first energization of the sender stepping relay 530 in the well-known manner. Thus, upon the first deenergization of stepping relay 530, the No. 0° counting relay 542 energizes in parallel with relay 532 and at its armature and front contact closes the previously traced circuit for advancing sender sequence switch 527 out of position 4 into position 6. Upon leaving position 4, the locking circuit of relays 541 and 542 is opened at the contact of cam 538. Relay 532 upon energizing opens the fundamental circuit at its armature and back contact thereby causing the deenergization of relay 228 of the district selector switch as soon as the brush 248 engages the next insulating portion of segment 249.
- Relay 228 upon deenergizing opens at its inner right-hand armature and front contact the previously traced circuit of the updrive magnet 238, thereby arresting the upward movement of the switch shaft for positioning the tripped set of brushes beneath the first group of terminals in the bank. At its inner right-hand armature and back contact, relay 228 closes the previously traced circuit for driving sequence switch out of position 6 and into position 7. In position 7, relay 228 energizes over a circuit extending from battery through its right-hand winding, the upper contacts of cam 204, the right-hand armature and front contact of relay 226 and thence to ground at the upper right-hand contact of cam 205 (17 to 15). Relay 228 upon energizing closes a circuit for driving sequence switch 200 out of position 7 and into position 8, which circuit may be traced from battery through the magnet winding of the sequence switch, the lower right-hand contact 130

of cam 206, the inner right-hand armature and front contact of relay 228, the upper left-hand contact of cam 207 (7 to 8) and thence to ground at the right-hand armature and front contact of relay 227.

As soon as sequence switch 200 leaves position 7, the initial energizing circuit of relay 228 is opened at the contact of cam 204, but relay 228 locks up over a circuit extending from battery through its left-hand winding, its left-hand armature and front contact, the upper left-hand and lower right-hand contacts of cam 216, the outer right-hand armature and front contact of relay 228, the lower contact of cam 224 to the test brush 252, and if the first trunk of the selected group is busy to ground at the test terminal 253 of such busy trunk. Upon reaching position 8 with relay 228 energized, the previously traced circuit for the updrive magnet 238 is established and the magnet 238 again drives the switch shaft upwardly in search of an idle trunk in the selected group. So long as the test brush 252 encounters the terminals of busy trunks, the relay 228 remains locked up. When, however, an idle trunk is encountered, which, it will be assumed, is the trunk terminating in the terminals 255, 256 and 257, the locking circuit of relay 228 is opened and relay 228 deenergizes, as soon as the brushes 252, 258 and 259 have been properly centered on the bank terminals 255, 256 and 257. Until the brushes are so centered, relay 228 remains locked up over a circuit extending through its right-hand winding, the right-hand contacts of cam 217, the brush centering segment 260, brush 261, the upper left-hand contact of cam 208, the inner right-hand armature and front contact of relay 228 and thence to ground at the right-hand contact of cam 207. Upon deenergizing, the circuit of the updrive magnet 238 is opened at the inner right-hand armature and front contact of relay 228 and the upward movement of the switch shaft is thereby arrested and a circuit is closed at the inner right-hand armature and back contact of relay 228 for driving sequence switch 200 out of position 8 and into position 9. Upon reaching position 8½ busy ground potential is connected to the multiples of test terminal 255 of the selected trunk over brush 252, commutator brush 251, overflow segment 279 and to ground through the upper right-hand and lower left-hand contacts of cam 216.

Relay 228 again energizes when sequence switch 200 reaches position 9 over the circuit extending from battery through its right-hand winding, the upper contacts of cam 217, the upper contact of cam 218 (1 to 10) and thence to ground at the armature and front contact of relay 261. Relay 261 is at this time energized over a circuit extending from

battery, through its winding, the left-hand contacts of cam 215, wiper 245 of sender finder SF, thence to ground at the contact of sequence switch cam 547 over the circuit previously traced. Relay 228 upon energizing closes the previously traced circuit through its inner right-hand armature and front contact for driving sequence switch 200 out of position 9 and into position 10, in which position the fundamental circuit is extended through the contacts of sequence switch cams 219 and 220, through brushes 258 and 259, respectively, to the line relay of the incoming selector switch 300.

Upon the extension of the fundamental circuit to the incoming selector switch, a circuit is closed from battery, through the right-hand winding of relay 301, the right-hand contacts of cam 302, associated with the sequence switch (not shown) of the incoming selector switch, conductor 303, resistance element 304, the upper contact of cam 305, trunk conductor 306, bank terminal 257, brush 259, the upper left-hand and lower right-hand contacts of cam 220, conductor 262, the outer right-hand armature and front contact of relay 230, wiper 237, conductor 528, the armature and back contact of relay 529, sender stepping relay 530, the winding of overflow relay 531, the armature and back contact of relay 532, the upper contact of sequence switch cam 533 (6), conductor 548, wiper 263, the left-hand armature and front contact of relay 244, conductor 264, the lower right-hand and upper left-hand contacts of cam 219, brush 258 and bank terminal 256 of the district selector 250, trunk conductor 307, the lower contact of cam 308, resistance element 309 and thence to ground at the lower contact of cam 310 (1 to 8). Relay 301 energizes in this circuit and at its armature and front contact closes a locking circuit for itself extending through its right-hand winding, lower contacts of sequence switch cam 302, the armature and front contact of relay 301, the contacts of sequence switch cam 311, thence as previously traced over the fundamental circuit and in the well-known manner establishes a circuit for advancing the switch shaft of the incoming selector switch in its brush selection movement. During the upward movement of the switch shaft, the sender stepping relay 530 is intermittently energized and deenergized in the well-known manner, to energize and lock up successive pairs of counting relays. Assuming that the calling subscriber has at this time dialed the thousands digit 9 and has, therefore, set the thousands register in position 9, five pairs of counting relays will be energized and locked up in succession and when the 0' counting relay 542 becomes energized, the sequence switch 527 of the sender will be advanced out of position 6

and into position 8 in the well-known manner. Relay 532 which energizes in parallel with the 0' counting relay 542 opens the fundamental circuit at its armature and 5 back contact and relay 301 at the incoming selector switch deenergizes, thereby arresting the upward movement of the switch shaft of the incoming selector 300. Following the deenergization of relay 301, the 10 sequence switch (not shown) of the incoming selector advances to such a position as to control the selector switch in its group selection movement.

Upon the termination of the brush selection movement of the switch shaft of the 15 incoming selector switch, the tripping magnet (not shown) of the incoming selector is operated preparatory to tripping the selected set of brushes upon a subsequent upward movement of the switch shaft and thereafter in the well-known manner with the sequence switch of the sender in position 8. The selected set of brushes is advanced 20 to a predetermined group of bank terminals in accordance with the setting of the thousands and hundreds registers of the office 25 sender.

Upon the completion of the group selection movement of the incoming selector switch, the sender sequence switch 527 advances to position 10 preparatory to controlling the brush selection movement of the final selector switch 350 and the incoming selector switch functions in the well-known manner to select an idle trunk extending 30 to an idle final selector switch. As soon as such idle trunk is found, the sequence switch of the incoming selector switch 300 advances to position 8 to extend the fundamental 35 circuit to the final selector switch. The fundamental circuit may be traced in part from ground at the lower contact of cam 316, through resistance element 309, the lower contact of cam 308, trunk conductor 307, thence as previously traced to the office 40 sender and through the winding of sender stepping relay 530 and returning over conductor 306, the upper contact of cam 305, resistance element 304, conductor 303, the upper contact of cam 312 (8), brush 313 of 45 the incoming selector switch and thence through the controlling relay (not shown) of the final selector switch to battery in the well-known manner. A holding circuit is 50 also established at this time for relay 301 which may be traced from grounded battery through the winding of relay 301, the lower contacts of cam 302, armature and front contact of relay 301, the lower contact of cam 314 (7 to 8), brush 315 and thence to ground 55 through the left-hand contacts of cam 316 associated with the sequence switch (not shown) of the final selector switch 350. This locking circuit for relay 301 is maintained until the sequence switch of the final

selector leaves position 8½ or until all of the selective movements of the final selector switch have been accomplished. Hundreds, tens and units selection are accomplished at the final selector switch 350 with the sequence switch 527 of the office sender in positions 10, 12 and 14 respectively, in accordance with the setting of the hundreds, tens and units registers of the office sender in the manner fully set forth in the application of E. H. Mills hereinbefore referred to, and following units selection and the energization of counting relay 542, the sender sequence switch is advanced to position 15. With sequence switch 527 in position 15, the sequence switch, cams of which are illustrated within the dotted rectangle, Fig. 5, is advanced out of position 13, opening the previously traced locking circuit of relay 400 at the contact of cam 565. Relay 400, 55 upon deenergizing, reconnects the winding of impulse relay 512 with the calling line over the impulse leads 233 and 235.

Upon units selection is completed and the sequence switch associated with the final selector switch leaves position 8½, the previously traced circuit of relay 301 is opened at the lower contact of cam 316 and relay 301 in the well-known manner causes the advance of the sequence switch associated with the incoming selector 300 out of position 8 into position 9. The winding of relay 301 is now connected in series with the windings of the overflow relay 531 and stepping relay 530 at the office sender and current now flows in such a direction through the windings of relay 531 as to cause its energization. This circuit may be traced from battery through the right-hand winding of relay 301, the lower contacts of cam 317, resistance element 309, the lower contact of cam 308, thence over the circuit previously traced through the windings of sender stepping relay 530 and polarized overflow relay 531 and returning over conductor 306, the upper contact of cam 305, resistance element 304, conductor 303, the contacts of cam 311 and thence to ground through the contacts of cam 318.

The energization of relay 301 in the circuit previously traced advances the sequence switch of the incoming selector into position 10 in the manner set forth in the aforesaid application. The energization of stepping relay 530 closes a circuit for the No. 0 counting relay 541 which may be traced from battery, through the winding of relay 541, lead 549, the contact of cam 550 (15), and thence to ground at the armature and contact of stepping relay 530. Counting relay 541 upon energizing locks up in series with the No. 0' counting relay 542 over the previously traced locking circuit and as soon as the sequence switch of the incoming selector switch moves out of position 9 and

relay 530 becomes deenergized, the No. 0' counting relay 542 becomes energized closing at its armature and front contact a circuit for advancing the sender sequence switch 527 out of position 15 into position 16. Relay 531 upon energizing in the previously traced circuit closes a circuit for the advance relay 545, which may be traced from battery through the winding of relay 545 and thence to ground at the armature and contact of relay 531. Relay 545 upon energizing closes a locking circuit for itself extending through its winding, left-hand armature and front contact and thence to ground through wiper 510 of switch TM. At its right-hand armature and front contact relay 545 opens the shunt around resistance element 551, thereby decreasing the current flowing over conductor 544 and through the winding of marginal relay 261 to such an extent that relay 261 thereupon becomes deenergized and opens the circuit of relay 228 which thereupon deenergizes and advances sequence switch 200 out of position 10 and into position 11. A circuit is now established extending through the left-hand winding of relay 228 at the district selector and the winding of sender stepping relay 530 for controlling the sequence switch 200 of the district selector in its talking selection movement. This circuit may be traced through the left-hand winding of relay 228, the lower left-hand contact of cam 210 (11), the upper left-hand contact of cam 210 (11 to 14), conductor 262, the outer right-hand armature and front contact of relay 230, wiper 237 of switch SF conductor 528, the armature and back contact of relay 529, the winding of sender stepping relay 530, the winding of relay 531, the armature and back contact of relay 532 and thence through the lower contact of cam 533 (16) and resistance element 534 to ground. Relay 228 upon energizing closes a circuit as previously traced for driving sequence switch 200 out of position 11 and into position 15, unless this circuit is interrupted at the armature contacts of relay 228 prior to the sequence switch reaching position 15. As soon as sequence switch 200 leaves position 11, relays 230 and 244 are maintained energized over a circuit which may be traced from battery through the winding of stepping magnet 229 of switch SF, the windings of relays 230 and 244 in parallel, the lower contact of cam 214 (11 to 14), the right-hand armature and front contact of relay 244, the upper right-hand contact of cam 215 (11 to 14), the outer right-hand armature and front contact of relay 228 and thence to ground through the lower contacts of cam 216.

During the rotation of sequence switch 200 from position 11 and into position 15, an intermittent ground is connected to the

fundamental circuit extending through the windings of relays 530 and 228 between the windings of these two relays in such a manner as to hold the relay 228 energized and to intermittently shunt out relay 530. This shunt circuit may be traced from battery through the left-hand winding, left-hand armature and front contact of relay 228 and thence to ground through the left-hand contacts of cam 216 and is closed in position 11½, 12½, 13½ and 14½.

With the sender sequence switch 527 in position 16 and sender stepping relay 530 energized and assuming that the code which the calling subscriber has set up has so prepared the circuits of the sender as to prepare a circuit for the No. 0 counting relay 541, the No. 0' counting relay 542 will become energized in series with relay 541 upon the first deenergization of stepping relay 530 when the sequence switch 200 of the district selector is passing through position 11½ and the previously traced circuit will be established for advancing sequence switch 527 out of position 16 into position 1. Upon the energization of counting relay 542, relay 532 energizes in parallel therewith and at its armature and back contact opens the previously traced circuit extending through the windings of sender stepping relay 530 and the winding of relay 228. Relay 228 upon deenergizing opens the previously traced circuit extending through the magnet winding of sequence switch 200 for arresting sequence switch 200 in position 12.

With the sequence switch of the district selector in position 12 and the sequence switch of the incoming selector in position 10, a circuit is established for relay 301 of the incoming selector switch which may be traced from battery through the right-hand winding of relay 301, the right-hand contacts of cam 302, conductor 303, resistance element 304, the upper contact of cam 305, conductor 306, bank terminal 257 and wiper 259 of the district selector switch, the left-hand contacts of cam 220, the upper right-hand winding of repeating coil 265, the lower contacts of cam 221, the windings of polarized relay 266, the upper contacts of cam 222, the lower right-hand winding of repeating coil 265, the upper contacts of cam 219, brush 258 and bank terminal 256 of the district selector, conductor 307, the lower contact of cam 308, resistance element 309 and thence to ground at the lower contact of cam 310. Relay 301 energizes in this circuit, but the current flowing in the circuit is not in such a direction as to cause the energization of polarized relay 266. In the manner fully set forth in the aforesaid application, relay 301 functions to initiate the application of ringing current to the called subscriber's line B.

As soon as the called subscriber responds, the application of ringing current is ar-

rested and the sequence switch of the incoming selector moves into the talking position 16 and a circuit is thereupon established for the supervisory relay 319, which may be traced from the non-grounded pole of battery through the lower right-hand winding of repeating coil 320, the winding of relay 319, the upper contact of cam 314, brush 315, the upper contacts of cam 316, brush 321, terminal 322, thence over the called subscriber's line loop, terminal 323, brush 324, the lower contact of cam 312 and thence to ground through the upper right-hand winding of repeating coil 320.

15 Relay 319 upon energizing in this circuit connects the terminals of central station battery to the windings of the polarized relay 266 at the district selector in such a manner as to cause the energization of relay 266. The circuit over which relay 266 is energized may be traced from the non-grounded pole of central station battery, through the upper contact of cam 310 (11 to 16), resistance element 309, the upper contacts of cam 317 (11 to 16), the lower left-hand winding of repeating coil 320, the upper contact of cam 308 (11 to 16), conductor 307, bank terminal 256 and brush 258, thence over the circuit previously traced, through the winding of polarized relay 266, brush 259, bank terminal 257, conductor 306, the lower contact of cam 305 (11 to 16), the upper left-hand winding of repeating coil 320, resistance element 304, conductor 303 and thence to ground at the armature and front contact of relay 319.

20 Relay 266 upon energizing in this circuit closes a circuit for relay 267 as soon as cam 268 has rotated to such a position as to close cam spring 269. This circuit may be traced from battery, through the contact of cam spring 269, the winding of relay 267, the left-hand contacts of cam 217, the contact of polarized relay 266 and thence to ground at the right-hand contact of cam 209. Relay 267 upon energizing closes a locking circuit for itself from battery, through its right-hand armature and front contact and thence to ground over the circuit previously traced independently of cam spring contact 269. As soon as cam 268 rotates to such a position as to open the spring contact 269 and close spring contact 270, a circuit is established for relay 261 which may be traced from battery through the winding of relay 261, the left-hand armature and front contact of relay 267 and thence to ground at spring contact 270. Relay 261 upon energizing closes a locking circuit for itself independent of cam spring contact 270 which may be traced from battery through the winding of relay 261, the left-hand contact of cam 218 (12 to 18), thence to ground through the right-hand armature and front contact of relay 261.

25 At its left-hand armature and front contact, relay 261 prepares a charging circuit which is effective to charge a call against the calling subscriber following the termination of the conversation and the advancement of sequence switch 200 into position 17. With sequence switch 200 in position 12 for talking, talking current is supplied to the calling subscriber over a circuit which may be traced from the non-grounded pole of central office battery, through the lower left-hand winding of repeating coil 265, the upper contact of cam 213, the winding of supervisory relay 234, conductor 116, wiper 111, the innermost lower armature and front contact of relay 102, conductor 103, thence over the subscriber's line loop, conductor 104, the upper armature and front contact of relay 102, wiper 113, conductor 117, the lower right-hand contact of cam 212 and thence to the grounded pole of battery through the upper left-hand winding of repeating coil 265. Relay 234 energizes in this circuit and at its armature and front contact closes a locking circuit to maintain relay 227 energized, which may be traced from battery, through the left-hand winding of relay 227, the armature and front contact of relay 234 and thence to ground at the right-hand armature and front contact of relay 227. The called subscriber receives talking current over the circuit previously traced, through the right-hand winding of repeating coil 320 and the calling and called subscribers are now connected over a talking circuit indicated in the drawings by the heavy conductors.

30 During the functioning of the office sender, the sequence switch, certain of the cams of which are shown in the dotted rectangle in Fig. 5, was positioned in position 9 in the manner fully set forth in the aforesaid application of E. H. Mills and at the contact of cam 552 a circuit was closed for advancing the time measure switch TM into position 16, this circuit extending from battery through the winding of stepping magnet 502, wiper 508, terminals of the bank with which this wiper is associated and thence to ground at cam 552, and the time measure switch TM remains in position 16 until the sender has fully functioned. Following the completion of the dialing of the seven digits of the desired number, the register steering switch RS is arrested in position 7 and a circuit is established over wiper 523 and bank terminal 554 for advancing the monitoring switch M out of position 7 through the energization of relay 410. The circuit for relay 410 may be traced from battery through the right-hand winding of relay 410, wiper 417, the No. 7 of the terminal of the bank with which this wiper is in engagement, conductor 428, bank contact 554, wiper 523 and thence to ground at the left-hand armature and front contact of relay 517. Upon the energization of relay 410, a circuit is established for step-

ping magnet 418 which may be traced from battery through the winding of magnet 418, the armature and contact of magnet 418, the right-hand armature and front contact of relay 410 and thence to ground as previously traced at the left-hand armature and front contact of relay 517. Magnet 418 advances the wipers of switch M until wiper 417 leaves the No. 8 terminal of the bank when relay 510 deenergizes and opens the circuit of magnet 418. A new stepping circuit for magnet M is now established from battery, through the winding of magnet 418, the right-hand armature and back contact of relay 410, the slow interrupter 419, the inner left-hand armature and back contact of relay 420, the No. 9 terminal of the bank with which wiper 477 is in engagement, wiper 477, the inner left-hand armature and back contact of relay 410 and thence to ground at the intermediate right-hand armature and front contact of relay 405. Under the influence of interrupter 419, the switch M is advanced into position 11.

As the wipers of the switch M pass through positions 9 and 10, a circuit is established for relay 400 which may be traced from battery on conductor 411, through the winding of relay 429, the winding of relay 400, the outer left-hand armature and front contact of relay 416, the Nos. 9 and 10 terminals of the bank with which wiper 423 engages, wiper 423, the outer right-hand armature and back contact of relay 410 and thence to ground at the intermediate right-hand armature and front contact of relay 405. Relay 400 upon energizing in this circuit closes a locking circuit for itself independent of wiper 423 which may be traced from battery on conductor 411, through the winding of relay 429, winding of relay 400, the inner right-hand armature and front contact of relay 400, conductor 430, the contacts of sequence switch cam 565, thence to ground at the armature and front contact of relay 501.

At the back contact of its outer right-hand and outer left-hand armatures, relay 400 opens the circuit previously traced extending from the subscriber's line through the windings of register stepping relay 512 and retardation coil 516 and connects the subscriber's line with the windings of marginal differential relays 414 and 431. The disconnection of the winding of relay 512 from the subscriber's line loop does not cause the release of relay 512, since this relay is maintained energized over a locking circuit which may be traced from battery through the winding of relay 512, conductor 513, the inner left-hand armature and front contact of relay 400, conductor 432 and thence to ground at the left-hand armature and front contact of relay 517. The energizing circuit for relays 414 and 431 may now be being traced from the source 460 of negative current, which is preferably of 110 volts potential through the left-hand armature and front contact of relay 429, the inner left-hand armature and back contact of relay 412, the outer right-hand armature and back contact of relay 415, the left-hand windings of marginal differential relays 414 and 431, bank terminals Nos. 9, 10 and 11 to which the wiper 406 has access, wiper 406, the outer right-hand armature and front contact of relay 400, the outer right-hand armature and back contact of relay 401, conductor 402, thence as previously traced to the subscriber's line and returning over conductor 403, the outer left-hand armature and back contact of relay 401, the outer left-hand armature and front contact of relay 400, wiper 433 and the Nos. 9, 10 and 11 bank terminals to which this wiper has access, the right-hand windings of relays 431 and 414, the inner left-hand armature and back contact of relay 415 and thence to ground at the outer right-hand armature and front contact of relay 405. Relays 414 and 431 being differentially wound do not energize in this circuit.

It will be assumed that the calling subscriber deposited the required coin or token in his coin device either before dialing the number of the called line or immediately following the dialing of the number and that, therefore, at the time the dialing was completed and the monitoring switch M reached position 9, an effective energizing circuit for relay 414 was established. This circuit may be traced from the source 460 of negative current, through the left-hand armature and front contact of relay 429, the inner left-hand armature and back contact of relay 412, the outer right-hand armature and back contact of relay 415, the left-hand windings of relays 414 and 431, wiper 406, the outer right-hand armature and front contact of relay 400, the outer right-hand armature and back contact of relay 401, conductor 402, the inner left-hand armature and front contact of relay 505, conductor 515, wiper 232, the outer left-hand armature and front contact of relay 230, conductor 233, the lower left-hand contact of cam 212, conductor 117, wiper 113, the upper armature and front contact of relay 102, conductor 104 the winding of coin collection magnet 126 and thence to ground through the contacts 127, which were operated upon the deposit of the coin. Relay 414 energizes in series with the winding of magnet 126, but relay 431 being marginally wound does not energize and polarized magnet 126 does not receive sufficient current through the winding of relays 414 and 431 to energize at this time. Relay 414 upon energizing opens the previously traced locking circuit of relay 409, and relay 409 upon

deenergizing opens the circuit of relay 416 which, in turn, opens the circuit of relay 529, so that when the sender sequence switch 527 reaches position 14 preparatory to controlling units selection, relay 529 will not become energized to hold the fundamental circuit open at its armature and contact. If the calling subscriber had not deposited the coin, then relay 414 would not then 10 energize as previously described and when sequence switch 527 of the sender reached position 13, a circuit would have been established for relay 529 which may be traced from battery through the contact of cam 15 555 (13 to 14), relay 529 conductor 556 and thence to ground at the right-hand armature and front contact of relay 416.

If the calling subscriber has not deposited the coin at the time switch M reaches position 11, the coin lamp 434 is caused to flicker over a circuit which may be traced from battery through the lamp 434, the outer left-hand armature and back contact of relay 412, the inner left-hand armature and front 20 contact of relay 416, interrupter 435, the normally closed contacts associated with the inner right-hand armature of relay 415, bank terminal 436, wiper 423, the outer left-hand armature and back contact of relay 25 410 and thence to ground at the intermediate right-hand armature and front contact of relay 405. The flickering of lamp 434 signals the monitoring operator that either the calling subscriber has deposited no coin or 30 that the coin is stuck in the coin chute and the monitoring operator may then take such steps as are necessary to obtain the deposit of the coin, or the clearing of the trouble. During the operation of coin lamp 434, the 35 pilot lamp 424 is operated over a circuit which may be traced through lamp 424, bank terminal 437, wiper 477, the inner left-hand armature and back contact of relay 410 and thence to ground at the intermediate 40 right-hand armature and front contact of relay 405.

If when the time measure switch M reaches position 9 the calling subscriber has properly deposited the coin and consequently the circuits of relays 409 and 416 are open due to the energization of relay 414, a circuit is closed for advancing the time measure switch M from position 9 into position 15 through the operation of relay 410. 45 The circuit of relay 410 may be traced from battery through the right-hand winding of the relay, wiper 417 and bank terminals 9 to 14 with which it contacts during its advancement, and thence to ground at the right-hand armature and back contact of relay 416. Relay 410 upon energizing closes the previously traced circuit for the stepping magnet 418, which circuit is maintained until wiper 417 leaves terminal 14 of its 50 bank, when relay 410 deenergizes and opens

the circuit of the magnet 418. In position 15, relay 410 is again energized over wiper 417, the inner left-hand armature and back contact of relay 415 to ground at the outer right-hand armature and front contact of 70 relay 405 and the previously traced circuit is again established through stepping magnet 418 for advancing the switch M into position 18. Relay 410 deenergizes as soon as the switch M reaches position 18, and closes 75 a new circuit for advancing the switch M into position 21, which circuit may be traced from battery through the winding of magnet 418, the right-hand armature and back contact of relay 410, interrupter 419, the inner 80 left-hand armature and back contact of relay 420, the bank contacts with which wiper 477 is associated, wiper 477, the inner left-hand armature and back contact of relay 410 and thence to ground at the intermediate 85 right-hand armature and front contact of relay 405.

If at the time the wipers of the time measure switch M reach position 21, the sender has not functioned to set up the desired connection, the lamp 421 is flickered to denote a stuck sender. The circuit of lamp 421 may be traced from battery through the lamp, the inner left-hand armature and back contact of relay 416, interrupter 435, 90 bank terminal 438, wiper 423, the outer left-hand armature and back contact of relay 410 and thence to ground at the intermediate 95 right-hand armature and front contact of relay 405.

The pilot lamp 424 is also lighted at this time over a circuit which may be traced through conductor 439, wiper 477, and thence to ground at the intermediate right-hand armature and front contact of relay 100 405. Under the assumption that the establishment of the connection proceeded without interruption in the manner hereinbefore described, as soon following units selection as the sequence switch of the district selector advances out of position 10, the impulse leads 233 and 235 which up to the time sequence switch 200 leaves position 10½ are connected with the winding of register stepping relay 512 and the winding of retardation coil 516, are disconnected from the district selector trunk conductors 116 and 117 at the contacts of sequence switch cams 212 and 213. Upon the opening of the circuit over impulse leads 233 and 235, relay 105 512 deenergizes, opening the circuit of slow releasing relay 517, which, upon deenergizing, closes a circuit extending from ground through the armature and back contact of relay 512, the right-hand armature and back contact of relay 517, restoring segment 557 110 of the switch RS, wiper 524 and thence to battery through the armature contact and winding of stepping magnet 522. Under 115

the influence of magnet 522, the switch RS 120 deenergizes, opening the circuit of slow releasing relay 517, which, upon deenergizing, closes a circuit extending from ground through the armature and back contact of relay 512, the right-hand armature and back contact of relay 517, restoring segment 557 of the switch RS, wiper 524 and thence to battery through the armature contact and winding of stepping magnet 522. Under 125 the influence of magnet 522, the switch RS 130

is restored to its normal position. Following the restoration of the switch RS, the code and numerical registers of the sender are restored and all the circuits of the sender 5 are placed in their normal position so that the sender may be employed in the establishment of other connections.

Release of sender.

10 Upon the completion of talking selection and the deenergization of relay 228 of the district selector switch, relays 230 and 234 become deenergized, since their locking circuit is now opened at the outer right-hand 15 armature and front contact of relay 228, and relay 230 upon deenergizing, opens the previously traced circuit of relay 501. Relay 501 upon deenergizing closes a restoring circuit for the time measure switch TM, which may be traced from battery through the winding of stepping magnet 502, the armature and back contact of this magnet, wiper 558, the terminals of restoring bank 559 and thence to ground at the armature 20 and back contact of relay 501. Under the influence of magnet 502, the time measure switch is restored to normal position. Upon the deenergization of relay 501, the holding 25 circuits of relays 505 and 405 are opened at the armature and front contact of relay 501 and these relays thereupon become deenergized. The deenergization of relay 505 disconnects the impulse leads 514 and 515 30 and the deenergization of relay 405 closes a circuit for restoring the monitoring time switch M into its normal position.

Upon the deenergization of relay 405, a circuit is established for relay 410 extending from battery through the right-hand winding of relay 410, the off-normal terminals of the restoring bank 440, wiper 441 and thence to ground at the outer left-hand armature and back contact of relay 405. Relay 410 upon energizing establishes a circuit for the stepping magnet 418 extending from battery through the winding of magnet 418, the armature and back contact of the magnet, the right-hand armature and front contact of relay 410, the terminals of bank 440, wiper 441 and thence to ground 45 at the outer left-hand armature and back contact of relay 405. As soon as switch M reaches normal position, the circuit of magnet 418 is opened at wiper 441 and the switch M is arrested in its normal position.

Termination of conversation—seizure of an idle sender.

Upon the termination of the conversation, both the called and calling subscribers 60 restore their respective receivers to their switchhooks. At this time, relay 261 is energized as previously described. Upon the restoration of the calling subscriber's receiver to its switchhook, supervisory relay 65

234 deenergizes, opening the holding circuit of relay 227 and since the circuit through the right-hand winding of relay 227 is open at this time, the sender having been disassociated from the district selector, relay 227 deenergizes, closing a circuit for driving sequence switch 200 out of position 12 and into position 16, this circuit extending from battery through the winding of sequence switch magnet 200, the lower left-hand contact of cam 206 (12 to 17), the left-hand contacts of cam 223 and thence to ground at the normal contacts associated with the right-hand armature of relay 227. At its left-hand armature, relay 227 opens the previously traced locking circuit for relay 226 extending over the upper contact of cam 203 and establishes a new locking circuit therefor, which may be traced through the left-hand winding of relay 226, the normal contacts associated with the left-hand armature of relay 227, the lower right-hand contact of cam 203 and thence over the sleeve conductor 118 and to ground through the winding of relay 102 as previously described. As sequence switch 200 reaches position 16, a circuit is closed for relay 228 which may be traced from battery, through the right-hand winding of relay 228, the upper contacts of cam 204, the right-hand armature and front contact of relay 226, the upper right-hand and lower left-hand contacts of sequence switch cam 223 and thence to ground at the normal contact associated with the right-hand armature of relay 227. Relay 228 upon energizing, closes a circuit for driving sequence switch 200 out of position 16 and into position 17, which circuit may be traced from battery through the magnet winding of sequence switch 200, the lower right-hand contact of cam 206 (16), the inner right-hand armature and front contact of relay 228 and thence to ground at the right-hand contact of cam 207. Relay 228 upon energizing establishes a locking circuit for itself extending through its left-hand winding, its left-hand armature and front contact, the lower right-hand contact of cam 210, the lower left-hand contact of cam 211 (16 to 17), the outer left-hand armature and front contact of relay 226, wiper 231 and thence to ground at the contact of the bank with which wiper 231 is then in engagement, if the sender associated with the multiples upon which the wipers of the sender finder SF are then resting is at the time employed. When sequence switch 200 reaches position 17, a circuit is established for the stepping magnet 229 of the switch SF extending from battery through the armature contacts and winding of magnet 229, the lower contact of cam 208 (16 $\frac{1}{4}$ to 17), the inner right-hand armature and front contact of relay 228 and thence to ground at the right-hand contact 125

of cam 207. Under the influence of magnet 229, the wipers of switch SF are advanced over the multiples of conductors extending to office senders assigned to the group of 5 district selector switches in which the selector 250 is located, until the test wiper 231 encounters a bank terminal corresponding to an idle office sender when the previously traced locking circuit of relay 228 is opened 10 and relay 228 becomes deenergized, thereby opening the circuit of magnet 229. A circuit is now established for relays 230 and 244 which may be traced from battery through the armature and back contact and 15 winding of magnet 229, the windings of relays 230 and 244 in parallel, the lower right-hand and upper left-hand contacts of cam 204, the right-hand armature and front contact of relay 226 and thence to ground at the 20 upper right-hand contact of cam 205 (17 to 15).

Upon the energization of relay 230, the circuit previously traced for relay 501 is established and relay 501 energizes, closing 25 the previously traced circuit for advancing the time measure switch TM from normal into position 2. With the time measure switch TM in position 2, a circuit is established for relay 505 in the manner previously 30 described, and relay 505 upon attracting its armatures closes the previously traced circuit for advancing the time measure switch into position 6 for extending the impulsive leads through the contacts of relay 35 230, wipers 232 and 236 of switch SF and through the windings of relay 512 and retardation coil 516. Since the subscriber's receiver has been restored to its switchhook, relay 512 does not energize. Upon the advancement of the time measure switch TM 40 to position 6, with the register stepping relay 512 deenergized, a circuit is established for the wipe-out relay 560 which may be traced from battery through the winding of 45 this relay, the No. 6 terminal of the bank 561, wiper 562, the right-hand armature and back contact of relay 517 and to ground at the armature and back contact of relay 512. Relay 505 upon energizing also closes the 50 previously traced circuit for relay 405, which upon energizing, closes the previously traced locking circuit for itself extending over conductors 408 and 407 to the armature and front contact of relay 501. 55 With the sequence switch of the district selector in position 17, a circuit is closed over the lower contacts of cam 225 (17), the left-hand armature and front contact of relay 261, the right-hand non-inductive winding 60 of sleeve relay 226 and thence over the sleeve conductor 118 for applying current of higher potential to the conductor 118 for operating the message register 119 of the calling subscriber's line. Since the subscriber's line A is equipped with a coin 65

device the only purpose of the message register 119 is to afford a check on the number of coins which the coin device should contain after the termination of a certain number of successful connections. Immediately 70 upon the extension of the connection from the district selector switch to the office sender, assuming that the established connection has been successful, a circuit is established for the coin collection relay 412 which may 75 be traced from battery through the winding of relay 412, conductor 442, the contact of sequence switch cam 563, conductor 548, wiper 263 of the switch SF, the left-hand armature and front contact of relay 244, the 80 lower right-hand contact of cam 218 (16 to 17) and thence to ground at the right-hand armature and front contact of relay 261. It is to be noted in this connection that 85 since the subscriber's receiver is upon its switchhook at the time the sender is seized, and since no digits have been dialed, the sequence switches associated with the sender are therefore in normal position.

Upon the energization of relay 405, a circuit is established for relay 409 extending from battery, conductor 411, the winding of relay 409, the normal contact of the bank with which wiper 477 is in engagement, wiper 477, the inner left-hand armature and back contact of relay 410 and thence to ground at the intermediate right-hand armature and front contact of relay 405. Relay 409 upon energizing closes a locking circuit for itself independently of the wiper 477, extending from battery on conductor 411, through the winding of relay 409, the left-hand armature and front contact of relay 409, the outer right-hand armature and front contact of relay 412 and thence to ground at the armature and back contact of relay 443. At its right-hand armature and front contact, relay 409 establishes a circuit for relay 410, which may be traced from battery through the right-hand winding of relay 410, wiper 417 and the normal contact of the bank with which it is associated and thence to ground at the right-hand armature and front contact of relay 409. Relay 410, upon energizing closes the 105 previously traced stepping circuit for the stepping magnet 418 of the switch M for advancing the switch M into position 1. 110

As soon as the switch M reaches position 1, a circuit is established for relays 415 and 420 which may be traced from battery through the windings of these relays in parallel, conductor 444, the inner right-hand armature and front contact of relay 405, the position 1 terminal of bank 440, brush 441, the outer left-hand armature and front contact of relay 405, the normally closed contacts associated with the outer left-hand armature of relay 420, conductor 445, the left-hand armature and back contact of relay 115 120

125 130

525 and thence to ground at the armature and front contact of relay 560. Relay 420 upon energizing establishes a locking circuit for both relays 415 and 420 independent of wiper 411, which may be traced through the windings of relays 415 and 420 in parallel, thence through the outer left-hand armature and front contact of relay 420 and to ground at the armature and front contact of relay 560 over the circuit previously traced. Upon the energization of relay 409, a circuit is also established for relay 416 extending from battery on conductor 411, thence through the winding of relay 416 to ground at the right-hand armature and front contact of relay 409.

Upon the energization of relay 415, a circuit is established for relay 400 which may be traced from battery on conductor 411, 20 through the winding of relay 429, the winding of relay 400, the inner left-hand armature and front contact of relay 415 and thence to ground at the outer right-hand armature and front contact of relay 405. 25 Relay 400 upon energizing closes a locking circuit for itself extending from battery on conductor 411, over the circuit previously traced, through the winding of relay 400, the inner right-hand armature and front 30 contact of relay 400, conductor 420, the contacts of cam 565 and thence to ground at the armature and front contact of relay 501.

As soon as switch M leaves its normal position, the circuit of relay 410 is opened at 35 wiper 417, but when the switch reaches position 1, a new energizing circuit for relay 410 is established extending from battery through the right-hand winding of relay 410, wiper 417, the outer right-hand armature and front contact of relay 429 and thence to ground at the outer right-hand armature and front contact of relay 405. Relay 410, upon energizing, closes a circuit 40 for the stepping magnet 418 extending from battery through the winding, armature and back contact of magnet 418, the right-hand armature and front contact of relay 410, wiper 417 and thence to ground at the outer right-hand armature and front contact of relay 405, over the circuit previously traced. Through the operation of magnet 418, the switch M is rapidly advanced to position 5, when the circuit of relay 410 is opened at 45 wiper 417 and the circuit of stepping magnet 418 is opened. With relay 410 deenergized, a new circuit for magnet 418 is established extending from battery through the winding of magnet 418, the right-hand armature and back contact of relay 410, the fast interrupter 447, the inner left-hand armature and front contact of relay 420 and thence over position 5 bank terminal with which the wiper 477 is in engagement, wiper 477, the inner left-hand armature and back contact of relay 410 and

thence to ground at the intermediate right-hand armature and front contact of relay 405. Under the influence of interrupter 447, the stepping magnet 418 advances the wipers of switch M to position 7, in which 70 position, the stepping circuit of magnet 418 is extended over the circuit previously traced to the inner left-hand armature and front contact of relay 420, thence through the right-hand armature and front contact 75 of relay 420 to the position 7 terminal of the bank with which wiper 477 is in engagement and thence to ground as previously traced. Upon reaching position 8, the circuit of magnet 418 is completed over the circuit 80 previously traced through the inner left-hand armature and front contact of relay 420 for continuing the advance of switch M into position 11.

Call successful—collection of coin.

When the wipers of switch M reach position 5, a circuit is closed for applying coin collection current from the source 461 of positive current, through the inner right-hand armature and front contact of relay 429 through the winding of relay 443, the inner right-hand armature and front contact of coin collection relay 412, the outer right-hand armature and front contact of relay 415, thence in parallel through the bank terminals 448 and 449, wipers 406 and 433, the outer right-hand armature and front contact and outer left-hand armature and front contact of relay 400, the outer right-hand armature and back contact and outer left-hand armature and back contact of relay 401, thence over conductors 402 and 403 and over the circuit previously traced to conductors 103 and 104 of the subscriber's line A. As 105 at this time the subscriber's receiver is upon the switchhook current flows only over the tip conductor 104 of the line from the source 461 and through the coin magnet 126 and contacts 127 to ground in such a direction as 110 to cause the energization of polarized magnet 126 in such a manner as to collect the deposited coin. Relay 443 also energizes in series with magnet 126 and at its armature and back contact opens the previously traced 115 locking circuit of relay 409, and relay 409, upon deenergizing, opens the previously traced circuit of relay 416.

When the wipers 406 and 433 of switch M reach position 7, both conductors of the 120 subscriber's line are connected over the circuit previously traced through wipers 406 and 433, bank terminals 451 and 452 to ground through condenser 450 for the purpose of discharging the subscriber's line 125 from the charge of collection current which was applied for collecting the deposited coin.

When the wipers of switch M reach position 9, the right-hand and left-hand wind- 130

ings of differential relay 453 are connected respectively to the tip and ring conductors of the subscriber's line, over the circuit previously traced from the subscriber's line to 5 wipers 406 and 433 and thence through bank terminals 454 and 455 to battery through the windings of relay 453. If the calling subscriber following the collection of the coin has immediately removed his receiver 10 from the switchhook to initiate another call, or if the receiver is still on the hook and the coin has been properly collected, relay 453 does not energize over the circuit previously traced. If, however, the coin has stuck in 15 the coin chute and ground is still maintained on the tip conductor 104 of the subscriber's line at contacts 127 of the coin device, relay 453 becomes energized and closes a circuit for relay 409 which may be traced from 20 battery on conductor 411, through the winding of relay 409 and thence to ground at the armature and front contact of relay 453. Relay 409 upon energizing locks up over the circuit previously traced to ground at the 25 armature and back contact of relay 443, this relay having deenergized as soon as switch M moved out of position 6, and also closes the previously traced circuit for relay 416. When switch M now reaches position 11, the 30 circuit of stepping magnet 418 is opened at brush 477 and the switch is arrested. A circuit is now established for flashing the coin lamp 434 which may be traced from battery through lamp 434, interrupter 456, the inner 35 right-hand armature and front contact of relay 415, bank terminal 436, wiper 423, the outer left-hand armature and back contact of relay 410 and thence to ground at the intermediate right-hand armature and front 40 contact of relay 405. The flashing of lamp 434 at this time signifies to the operator that the coin is stuck in the coin chute at the calling subscriber's station, and the operator will thereupon initiate the necessary steps to 45 clear the trouble. If the coin is properly collected, relay 453 does not energize and consequently relays 409 and 416 do not energize. Therefore, when switch M reaches position 9, a circuit is established for rapidly 50 advancing the switch M into position 15 through the operation of relay 410, which energizes in a circuit which may be traced from battery through the right-hand winding of relay 410, wiper 417, position 9 terminal of the bank with which wiper 417 is 55 associated and thence to ground at the right-hand armature and back contact of relay 416. This circuit is maintained until the wipers of switch M advance out of position 60 14, the advancing circuit of the switch being closed through the magnet 418 and the armature and front contact of relay 410 and thence over the circuit previously traced to ground at the armature and back contact of 65 relay 416.

As soon as the wipers of switch M reach position 15, a circuit is established for relay 227 of the district selector switch which may be traced from battery through the right-hand winding of relay 227, the upper contact of cam 214 (17), the right-hand armature and front contact of relay 244, the lower contact of cam 215 (17), wiper 245, conductor 544 the inner left-hand armature and back contact of relay 545, conductor 564, position 15 terminal of the bank with which wiper 423 is in engagement, wiper 423, the outer left-hand armature and back contact of relay 410 and thence to ground at the intermediate right-hand armature and front contact of relay 405. This circuit is maintained while the switch M is advancing through positions 16 and 17 under the control of interrupter 447. Relay 227 upon energizing opens the previously traced locking circuit of relay 226 at the normally closed contacts associated with its left-hand armature, which opens the locking circuit over which relays 230 and 244 have been maintained energized. These relays thereupon deenergize, relay 230 opening the circuit of relay 501, which in the manner previously described, closes a circuit extending through bank 559 of switch TM, wiper 558 and the winding of stepping magnet 502 for restoring the time measure switch TM to normal position. As soon as switch TM reaches normal position, the circuit of relay 560 is opened and the previously traced locking circuit of relays 415 and 420 is 95 opened, and the locking circuit of relay 505 is also opened whereupon the leads 514 and 515 are disconnected from conductors 402 and 403. Relay 501 upon deenergizing also 100 opens the locking circuit of relay 405, which upon deenergizing, closes a circuit for relay 410 which may be traced from battery through the right-hand winding of relay 410, the contacts of bank 440, wiper 441 and thence to ground at the left-hand armature and back contact of relay 405. Relay 410 upon energizing closes a circuit for stepping magnet 418 which may be traced from 105 battery through the winding, armature and back contact of magnet 418, the right-hand armature and front contact of relay 410, contacts of bank 440, wiper 441 and thence to ground at the outer left-hand armature and back contact of relay 405. Under the influence of magnet 418, switch M is restored to normal position, whereupon the circuit of relay 410 is opened and thereby the restoring movement of the switch is arrested. Relay 501 upon deenergizing also 110 opens the locking circuit of relays 400 and 429 and these relays thereupon deenergize. All of the circuits of the office sender, which have been employed in the collection of the coin, have now been restored to normal position. 115

120

130

Restoration of switches.

At the district selector switch, upon the deenergization of relay 226, a circuit is closed for advancing the sequence switch 200 out of position 17 and into position 18, which may be traced from battery through the magnet winding of sequence switch 200, lower left-hand contact of cam 206 (12 to 17), the right-hand armature and back contact of relay 226 and thence to ground at the upper right-hand contact of cam 205 (17 to 15). As soon as sequence switch 200 leaves position 17, the energizing circuit of relay 227 is opened and relay 227 deenergizes. With sequence switch 200 in position 18, a circuit is closed for the down-drive magnet 271, which may be traced from battery through the winding of magnet 271, the lower contacts of cam 223 and thence to ground at the normally closed contacts associated with the right-hand armature of relay 227. Magnet 271 upon energizing presses the depending portion of switch shaft 239 against the constantly rotating down drive drum 272 and in the well-known manner causes the restoration of the switch shaft to its normal position. Upon reaching its normal position, a circuit is established for sequence switch magnet 200 which may be traced from battery through the winding of the sequence switch magnet, the upper right-hand contact of cam 206, normal commutator segment 273, brush 248 and thence to ground at the lower contact of sequence switch cam 209. The sequence switch magnet is energized in this circuit and advances the sequence switch into normal position. As soon as the sequence switch leaves position 18, the locking circuit of relay 261 is opened at sequence switch cam 218. The circuits of the district selector switch are now in normal condition.

Upon the opening of the circuits extending through the winding of sleeve relay 226 and the winding of relay 102, relay 102 becomes deenergized and at its lowermost armature and back contact closes the circuit of stepping magnet 105 for restoring the line switch 100 into normal position. The circuit of magnet 105 may be traced from battery through the winding, armature and back contact of magnet 105, conductor 106, the lowermost armature and back contact of relay 102, the right-hand armature and back contact of relay 101, conductor 125, wiper 112 and thence to ground on segment 124. As soon as the switch 100 reaches normal position, the circuit of magnet 105 is opened at wiper 112.

As soon as sequence switch 200 leaves position 14½, holding ground potential is removed from test brush 252 at the lower left-hand contact of cam 216 (8½ to 14½), and in the well-known manner, the release

of the incoming and final selector switches is initiated.

Call unsuccessful—refund of coin.

If the connection established to the called line had been unsuccessful, that is, the called subscriber failed to respond, then the call charging relay 261 of the district selector switch would not have energized when sequence switch 200 of the district selector was in position 12 and consequently, no circuit for the coin collection relay 412 would have been established upon the reassociation of the office sender with the district selector upon the termination of the call. Therefore, when the switch M reaches position 5 during its second cycle, current from the refunding source 460 becomes connected through the left-hand armature and front contact of relay 429, the inner right-hand armature and back contact of relay 412 and thence as previously traced to the subscriber's line. This current being of negative polarity, causes the energization of polarized magnet 126 of the subscriber's coin device in such a direction as to refund the coin.

Abandonment of call.

If the calling subscriber abandons the call at any time before the register steering switch RS reaches position 2, that is, after having dialed the first two code digits of the desired number, the stepping relay 512 at the register steering switch becomes deenergized and, in turn, opens the circuit of slow-to-release relay 517. The register steering switch thereupon restores to its normal position by means of a stepping circuit which may be traced from battery through the winding, armature and contact of magnet 522, wiper 524, off-normal segment 557, the right-hand armature and back contact of relay 517 and the armature and back contact of relay 512. A circuit is also closed at this time for relay 560 extending from battery through the winding of relay 560, the strapped contacts of bank 561, wiper 562, the right-hand armature and back contact of relay 517 and thence to ground at the armature and back contact of relay 512.

Relay 560 upon energizing now closes a circuit for advancing the monitoring switch M from position 7, in which it is standing, into normal position. This circuit may be traced from battery through the right-hand winding of relay 410, the strapped contacts of bank 440, wiper 441, the outer left-hand armature and front contact of relay 405, the normally closed contacts associated with the outer left-hand armature of relay 420, conductor 445, the left-hand armature and back contact of relay 525, this relay being deenergized at this time, and thence to ground at

the armature and front contact of relay 560. Relay 410 upon energizing closes a circuit for stepping magnet 418 which extends through the winding of the stepping magnet, the armature and contact of the magnet, the right-hand armature and front contact of relay 410 and thence over the circuit previously traced to ground at the armature contact of relay 560. When the switch M reaches normal position, a circuit is established for relays 420 and 415 which may be traced from battery through the windings of these relays in parallel, conductor 444, the inner right-hand armature and front contact of relay 405, the normal contact and wiper 441 of switch M, the outer left-hand armature and front contact of relay 405 and thence to ground at the armature and front contact of relay 560. Relays 420 and 415 upon energizing lock up to the conductor 445 through the outer left-hand armature and front contact of relay 420 independently of the wiper 441.

With the switch M in normal position, the previously traced circuit for relay 409 is established and relay 409 upon energizing locks up and establishes a circuit for relays 416 and 410. Relay 410 upon energizing establishes the previously traced stepping circuit for magnet 418 for advancing the switch M from normal position into position 1. Upon the energization of relay 415, the previously traced circuit is established for relay 409 and a circuit is also established for advancing switch M out of position 1 and into position 5, through the energization of relay 410. The circuit of relay 410 may be traced from battery through the right-hand winding of relay 410, wiper 417, the No. 1 terminal of the bank with which it is associated, the outer right-hand armature and front contact of relay 429 and thence to ground at the outer right-hand armature and front contact of relay 405. Relay 410 is maintained energized until the switch reaches position 5 and at its right-hand armature and front contact establishes the previously traced stepping circuit for magnet 418.

With relay 400 energized when the switch M reaches position 5, refunding current is connected to the subscriber's line from the source 460 over the circuit previously described in connection with the establishment of an unsuccessful call. The circuits of the switch M now function in the manner previously described and when the wiper 423 reaches position 15, direct ground is connected to conductor 564 for increasing the flow of current through the right-hand winding of relay 227 of the district selector, whereby relay 227 deenergizes.

Upon the deenergization of relay 227, the locking circuit extending through the winding of relay 226 and the winding of cut-off

relay 102 is opened, and these relays deenergize. Since at this time the sequence switch of the district selector has not advanced beyond position 7, a circuit is now closed for driving sequence switch 200 into position 7. 70 which circuit may be traced from battery through the winding of sequence switch magnet 200, the lower left-hand contact of cam 206, (2 to 6) the right-hand armature and back contact of relay 226 and thence to ground at the upper right-hand contact of cam 205. With sequence switch 200 in position 7, a circuit is established for the down-drive magnet 271 extending from battery, through the winding of the magnet 271, the 75 lower right-hand and upper left-hand contacts of cam 223 and thence to ground through the right-hand armature and back contact of relay 226 and the upper right-hand contact of cam 205. When the switch 80 shaft reaches normal position, a circuit is established for advancing sequence switch 200 into normal position, which circuit may be traced from battery through the magnet winding of sequence switch 200, the upper 85 right-hand contact of cam 206, normal segment 273, brush 248 and thence to ground at the lower contact of cam 209. Upon the deenergization of cut-off relay 102, the line switch 100 is restored in the manner previously described.

As soon as the sequence switch of the district selector leaves position 11, the locking circuits of relays 230 and 244 are opened and relay 230 upon deenergizing opens the previously traced circuit of relay 501. Relay 501 upon deenergizing causes the restoration of the time measure switch TM, the restoration of switch M and the deenergization of 95 relays 505 and 560 in the manner previously described.

If the calling subscriber abandons the call after dialing the second digit but before the fundamental circuit is closed for controlling the setting of the district selector in accordance with the office code digits dialed, relay 560 upon energizing closes a circuit over the contact of cam 570, through the right winding of relay 525, and relay 525 being differential deenergizes. With relay 525 deenergized, the previously traced circuit is closed for advancing switch M for refunding the coin and for releasing all operated apparatus.

If the calling subscriber abandons the call at any time after dialing the first three office code digits, the district selector is set in the manner previously described and relay 560 at its right armature and front contact connects the No. 0 counting relay lead to the lower right contact of cam 550 so that as the sender sequence switch 527 reaches positions 6, 8, 10 and 12 respectively, incoming brush and group and final brush and group selections are made even though 130

the subscriber may not have dialed any further digits. When the sequence switch 527 reaches position 14 for controlling units selection, no counting relay leads are connected and the final selector thereupon is set into its telltale position in the well known manner. Under this condition, the overflow relay 531 is operated and the district sequence switch is advanced into position 11 for talking selection, as previously described. Talking selection is then made, sequence switch 200 advancing out of position 11. When the district sequence switch 200 reaches position 12, since the calling subscriber has hung up his receiver and relays 234 and 227 are deenergized, the sequence switch 200 is advanced into position 16 and the connection is thereupon restored and the deposited coin refunded in the manner previously described in connection with an unsuccessful call.

From the foregoing description, it is apparent that if the calling subscriber abandons the call before it has progressed beyond a certain stage, the service charging controlling mechanism associated with the office sender is rendered effective to refund a deposited coin, and that if the call has progressed beyond a certain stage, the connection becomes fully established, the sender is disassociated, and upon the release of the connection by the calling subscriber, either following a successful or unsuccessful call, a sender is again reassociated with the established connection for either collecting or refunding a deposited coin.

What is claimed is:

1. In a telephone exchange system, a plurality of subscribers' lines, a group of connecting circuits and switches for establishing a talking connection from one of said lines to another, a service charging device associated with each of said lines respectively, sending mechanism for controlling said switches, electrically operated controlling mechanism individual to said sending mechanism for governing the operation of said charging devices, and means operative after completion of said connection for automatically associating said sending mechanism and associated controlling mechanism with any one of the group of connecting circuits employed in establishing said connection.

2. In a telephone exchange system, a plurality of subscribers' lines, a group of connecting circuits and switches for establishing a talking connection from one of said lines to another, a service charging device associated with each of said lines respectively, a sending mechanism for controlling said switches, electrically operated controlling mechanism individual to said sending mechanism for governing the operation of said charging devices, and a switch opera-

tive after completion of said connection for automatically associating said sending mechanism and associated controlling mechanism with any one of the group of connecting circuits employed in establishing said connection.

3. In a telephone exchange system, a plurality of subscribers' lines, connecting circuits and switches for establishing a talking connection from one of said lines to another, a service charging device associated with each of said lines respectively, a plurality of sending mechanisms any one of which may be employed for controlling said switches, an electrically operated controlling mechanism individual to each of said sending mechanisms for governing the operation of said charging devices, and means operative after completion of said connection for automatically associating an idle one of said sending mechanisms and associated controlling mechanisms with a connecting circuit employed in establishing a connection.

4. In a telephone exchange system, a plurality of subscribers' lines, connecting circuits and switches for establishing a talking connection from one of said lines to another, a service charging device associated with each of said lines respectively, a plurality of sending mechanisms any one of which may be employed for controlling said switches, an electrically operated controlling mechanism individual to each of said sending mechanisms for governing the operation of said charging devices, and a switch operative after completion of said connection for automatically associating an idle one of said sending mechanisms and associated controlling mechanisms with a connecting circuit employed in establishing a connection.

5. In a telephone exchange system, calling subscribers' lines, called subscribers' lines, connecting circuits and switches for establishing a talking connection from a calling line to a called line, a service charging device associated with each of said calling lines respectively, a plurality of sending mechanisms for controlling said switches, a controlling mechanism individual to each of said sending mechanisms for governing the operation of said charging devices, and means automatically responsive to the termination of a call by the calling subscriber for associating an idle one of said sending mechanisms and associated controlling mechanisms with the connecting circuit employed in establishing the connection.

6. In a telephone exchange system, calling subscribers' lines, called subscribers' lines, connecting circuits and switches for establishing a talking connection from a calling line to a called line, a service charging device associated with each of said call-

ing lines respectively, a plurality of sending mechanisms for controlling said switches, a controlling mechanism individual to each of said sending mechanisms for governing the 5 operation of said charging devices, and a switch automatically responsive to the termination of a call by the calling subscriber for associating an idle one of said sending mechanisms and associated controlling mechanisms with the connecting circuit 10 employed in establishing the connection.

7. In a telephone exchange system, calling subscribers' lines, called subscribers' lines, connecting circuits and switches for 15 establishing a talking connection from a calling line to a called line, a coin device associated with each of said calling lines respectively, a plurality of sending mechanisms for controlling said switches, a controlling mechanism individual to each of 20 said sending mechanisms for governing the operation of said coin devices during the establishment of connections, and a switch automatically responsive to the termination 25 of a call by the calling subscriber for associating an idle one of said sending mechanisms and associated mechanisms with the connecting circuit employed in establishing the connection.

30 8. In a telephone exchange system, calling subscribers' lines, called subscribers' lines, connecting circuits and switches for establishing a talking connection from a calling line to a called line, a service charging device associated with each of said calling lines respectively, a plurality of sending mechanisms for controlling said switches, a controlling mechanism individual to each of 35 said sending mechanisms for controlling the operation of said charging devices, means operative upon the initiation of a call to associate an idle sending mechanism with said connection for controlling said switches, means operative upon the complete establishment of said connection for dismissing said sending mechanism, and means operated responsive to the termination of a call by the calling subscriber for reoperating said switch for 40 reassociating an idle sending mechanism and controlling mechanism with the connecting circuit employed for governing said coin device to collect or refund a deposited coin dependent upon the success of the established connection.

45 9. In a telephone exchange system, a plurality of subscribers' lines, a group of connecting circuits and switches for establishing a talking connection from one of said lines to another, a dial and a service charging device associated with each of said lines respectively, a central office sending mechanism under the control of said dial for controlling said switches, controlling mechanism individual to said sending mechanism for governing the operation of said charging devices, and means operative after completion 50 of said connection for automatically associating said sending mechanism and associated controlling mechanism with any one of the group of connecting circuits employed in establishing said connection.

55 10. In a telephone exchange system, calling subscribers' lines, called subscribers' lines, connecting circuits and switches for establishing a talking connection from a calling line to a called line, a service charging device associated with each of said calling lines respectively, a plurality of sending mechanisms for controlling said switches, a controlling mechanism individual to each of said sending mechanisms for governing the operation of 60 said charging devices, a switch operative 65

upon the initiation of a call to associate an idle sending mechanism with said connection for controlling said switches, means operative upon the complete establishment of said connection for dismissing said sending mechanism, and means operated responsive to the termination of a call by the calling subscriber for reoperating said switch for reassociating an idle one of said sending mechanisms and controlling mechanisms with the connecting circuit employed 70 for governing said charging device.

11. In a telephone exchange system, calling subscribers' lines, called subscribers' lines, connecting circuits and switches for 75 establishing a talking connection from a calling line to a called line, a coin device associated with each of said calling lines respectively, a plurality of sending mechanisms for controlling said switches, a controlling mechanism individual to each of 80 said sending mechanisms for governing the operation of said coin device, a switch operative upon the initiation of a call to associate an idle sending mechanism with said connection for controlling said switches, means operative upon a premature release of a connection for causing said controlling mechanism to operate said coin device to 85 refund a deposited coin, means operative upon the complete establishment of said connection for dismissing said sending mechanism, and means operated responsive to the termination of a call by the calling subscriber for reoperating said switch for 90 reassociating an idle sending mechanism and controlling mechanism with the connecting circuit employed for governing said coin device to collect or refund a deposited coin dependent upon the success of the established connection.

12. In a telephone exchange system, a plurality of subscribers' lines, a group of connecting circuits and switches for establishing a talking connection from one of said lines to another, a dial and a service charging device associated with each of said lines respectively, a central office sending mechanism under the control of said dial for controlling said switches, controlling mechanism individual to said sending mechanism for governing the operation of said charging devices, and means operative after completion 100 of said connection for automatically associating said sending mechanism and associated controlling mechanism with any one of the group of connecting circuits employed in establishing said connection.

13. In a telephone exchange system, a plurality of subscribers' lines, connecting circuits and switches for establishing a talking connection from one of said lines to another, a dial and a service charging device associated with each of said lines respectively, a plurality of central office sending mechanisms 110

- nisms adapted to be controlled by said dials and any one of which may be employed for controlling said switches, a controlling mechanism individual to each of said sending mechanisms for governing the operation of said charging devices, and means operative after completion of said connection for automatically associating an idle one of said sending mechanisms and associated controlling mechanisms with a connecting circuit employed in establishing said connection.
13. In a telephone exchange system, a plurality of subscribers' lines, a group of connecting circuits and switches for establishing a talking connection from one of said lines to another, a coin device associated with each of said lines respectively, sending mechanism for controlling said switches, 20 coin collecting and refunding control mechanism individual to said sending mechanism for governing said coin devices, and means for automatically associating said sending mechanism and associated controlling mechanism with any one of the group of connecting circuits employed in establishing said connection.
14. In a telephone exchange system, a plurality of subscribers' lines, a group of connecting circuits and switches for establishing a talking connection from one of said lines to another, a coin device associated with each of said lines respectively,
- sending mechanism for controlling said switches, coin collecting and refunding control mechanism individual to said sending mechanism for automatically governing the operation of said coin devices, and means for automatically associating said sending mechanism and associated controlling mechanism with any one of the group of connecting circuits employed in establishing said connection.
15. In a telephone exchange system, a calling line, a called line, central office register senders, means for selecting an idle sender, means for establishing a connection between said lines under the control of said sender and means under the control of said calling line for reassociating a sender with the established connection.
16. The method of call charging control in an automatic system employing a sender for controlling the operation of the automatic switches which comprises associating a sender with a line upon initiation of a call, disassociating the sender from the line upon completing the connection, reassociating a sender with the line upon the termination of the call and operating the call charging device from the reassociated sender.
- In witness whereof, I hereunto subscribe my name this 31st day of December A. D., 1920.

WINFRED T. POWELL.
